UNITED STATES PATENT OFFICE

2,417,743

AIR CONDITIONING APPARATUS

Arthur H. Eberhart, Springfield, Mass., assignor
to Westinghouse Electric Corporation, East
Pittsburgh, Pa., a corporation of Pennsylvania

Application July 16, 1941, Serial No. 402,601

10 Claims. (Cl. 261—78)

1

My invention relates to air conditioning apparatus, more particularly to apparatus for spraying water into an air stream, and it has for an object to provide improved apparatus.

A more particular object is to provide apparatus for spraying water from a pan or the like into an air stream above, which apparatus requires no moving parts other than that which moves the stream of air.

In accordance with my invention, I provide a tab or strip of sheet metal or the like extending upwardly from the water, preferably in an inclined direction, into the air stream. I find that a suction is created on the downstream side of the tab or strip and draws the water upwardly along the strip, and that the water is then carried off in the air stream in the form of a spray.

My invention is particularly suitable as a condensate disposal means in an air-cooled room cooler. The condensate formed on the evaporator is sprayed into the condenser air stream, and preferably onto the condenser. I find that it is also suitable for a regular evaporative condenser, as it sprays sufficient water to effect substantially complete wetting of the outer or air-cooled surfaces of the condenser.

These and other objects are effected by my invention as will be apparent from the following description and claims taken in accordance with the accompanying drawings forming a part of this application, in which:

Fig. 1 is a vertical section showing an air cooled room cooler incorporating my invention;

Fig. 2 is a detail sectional view taken on the line II—II of Fig. 1;

Figs. 3 and 4 are elevational views showing a second embodiment of my invention;

Figs. 5 and 6 are elevational views of a third embodiment;

Fig. 7 is a plan view of a third embodiment;

Fig. 8 is a plan view of an evaporative condenser incorporating my invention; and

Fig. 9 is a side elevation of the evaporative condenser.

Figs. 1 and 2

Referring to the drawing in detail, I show a self-contained room cooler 10 which is mounted adjacent a window on the floor of the room which it serves. The room cooler 10 includes a housing or cabinet 11 and a refrigerating system contained within the housing. The refrigerating system includes an evaporator 12, a condenser 13, and a motor-compressor unit and expansion device (not shown), all connected in a complete refrigerant circuit in a well-known manner. The evaporator 12 is disposed in the upper part of the room cooler above a partition 14. The evaporator 12 comprises a plurality of parallel tubes 15 containing refrigerant at low temperature and a plurality of transverse plates or fins 16 provid-

ing extended heat transfer surfaces. Suitable provision is made to provide flow of air into the room cooler and to the rear of the evaporator, then forwardly over the surfaces of the tubes and fins of the evaporator, and for discharging the air upwardly through an outlet 17 into the room.

The condenser 13 is of any suitable construction, such as the conventional cross-fin coil. It is located just below the partition 14, and a centrifugal fan 18 is disposed below (for the most part directly below) the condenser for directing a stream of air onto and over the surfaces of the condenser. The fan 18 includes a rotor or blade wheel 19 mounted on a shaft 20, which may be driven by an electric motor (not shown). The fan further includes a convolute casing 21 disposed as shown in Fig. 1 with its outlet 22 at the top. A duct member 23 is connected to the outlet 22 and to the condenser, and serves to direct the air discharged from the fan casing onto the front and a portion of the bottom of the bank of condenser tubes. A window duct structure 24 provides communication with the window, and contains an inlet passage 25 for conveying outdoor air to a portion of the housing which communicates with the inlet of the fan 18 and an outlet passage 26 for conveying the air discharged from the condenser to outdoors, as clearly shown on the drawing.

30 A drip pan 27 is disposed under the evaporator 12 for collecting the moisture which is condensed on the surfaces of the evaporator from the air which is cooled thereby. The condensate drains by gravity through a conduit 28 into a pan 29 disposed at the bottom of the room cooler. The bottom of the blower casing extends down into the pan 29. At the lowermost point of the blower casing, a tab or strip 30 is cut out of the casing and bent to extend upwardly in an inclined direction as shown on the drawing. The hole in the casing formed by cutting out the tab 30 is designated 31. The lower end of the tab 30 is spaced about $\frac{1}{8}$ or $\frac{1}{16}$ inch from the bottom of the pan. Thus, the tab extends down into or sufficiently close to the water in the pan 29 to assure that the water will be drawn upwardly as hereinafter explained, while a space is also provided for flow of water from the pan into the opening 31.

40 The remaining parts of the room cooler, including the motor-compressor unit, the expansion device, the evaporator air fan and the motor for driving the fans, are not shown as they may be of any suitable known construction and arrangement so far as the present invention is concerned, reference being made to my copending application Serial No. 321,875, filed March 2, 1940, which discloses in greater detail a construction of room cooler to which the present invention is applicable.

2

Operation—Figs. 1 and 2

The refrigerating system in the room cooler operates in the usual manner of such apparatus, liquid refrigerant at reduced pressure being conveyed through the evaporator tubes to maintain the evaporator at a low temperature, and the hot compressed gaseous refrigerant being conveyed through the tubes of the condenser 13 for the purpose of dissipating the rejected heat from the refrigerating system. The air to be cooled flows forwardly over the evaporator and into the room. The evaporator is maintained at a sufficiently low temperature so that, ordinarily, it cools the air below its dew point, thereby condensing moisture out of the air. The moisture is collected in the drain pan 27 and conveyed by gravity through the conduit 28 to the pan 29.

The fan 18 operates to effect circulation of outdoor air over the tubes of the condenser in order to carry away the rejected heat, the air flowing inwardly through the passage 25 into the housing 11 and into the inlet of the fan 18. The fan discharges the air onto the surfaces of the condenser tubes, from which it flows through the passage 26 to outdoors. Within the fan casing 21, the air is rotated in counterclockwise direction, as seen in Fig. 1, so that at the bottom of the fan casing the air flows from left to right in a substantially horizontal direction. As the air passes the tab 30, it creates a suction on the downstream side of the tab. This suction draws water from the pan 29 upwardly along the back or downstream side of the tab. As the water moves upwardly, it is drawn into the air stream in the form of a spray and at least substantial portions thereof are carried along with the air onto the air cooled surfaces of the condenser 13. Particles of water which are too large to be carried by the air stream fall to the bottom of the fan casing and flow to the downstream side of the tab 30, from which they are again drawn upwardly and sprayed into the air stream. The water sprayed onto the air cooled surfaces of the condenser is evaporated by the heat supplied by the condenser and the resulting vapor is carried off with the air stream through the passage 26 to outdoors.

Figs. 3 and 4

In Figs. 3 and 4, I show a modified form of my invention in which the fan housing is disposed to discharge the air horizontally, the outlet extending down into a drain pan 32. The fan casing is formed with a channel or passage 33 through which water can flow from left to right, as seen in Fig. 3. A tab or strip 34 is spot-welded or otherwise fastened to the upper wall of the channel 33 and extends in an upwardly-inclined direction, as shown in Fig. 3.

In the operation of this embodiment, the air flowing horizontally past the strip 34 creates a suction on the back or downstream side of the strip. Accordingly, water in the pan is drawn up along the back of the strip and is then carried off into the air stream. The air stream may be directed onto an air cooled condenser, as in the first embodiment.

Figs. 5, 6 and 7

In Figs. 5, 6 and 7, I show an embodiment of my invention, the specific form of which was proposed by Knud J. Helsing and Joseph Scattoloni. In this embodiment, the fan is provided with an outlet passage 35 of some length. The

outlet passage 35 rests on the bottom of the pan 36. A plurality of upwardly-extending, inclined tabs or fingers 37 are placed in the blower casing adjacent the beginning of the passage 35, as shown in Fig. 5. The fan casing is formed with openings 38 disposed directly under the tabs 37 to provide for admission of the water which is to be sprayed. The length of the passage 35 beyond the tabs 37 provides for restricted air flow which improves the operation of the atomizing device. The blower casing is also provided with a deflector plate 39 at the bottom of the discharge end of the passage 35. This plate, by deflecting the air upwardly, assures that the water atomized at the tabs 37 will be blown upwardly when leaving the fan shroud. In addition, this plate keeps the fan from blowing the water in the drain pan away from the shroud. Accordingly, if there is water in the drain pan, it can flow to the openings 38, there to be drawn into the casing and sprayed as already described.

Figs. 8 and 9

In the first embodiment, the condenser serves as an evaporative condenser to the extent of the water which is available; namely, the moisture condensed from the air. The amount of this water, however, is not sufficient to effect complete wetting of the air cooled surfaces of the condenser. In Figs. 8 and 9, I show my invention incorporated in a regular evaporative condenser, that is, a condenser provided with an adequate supply of water to effect substantially complete wetting of the air cooled surface of the condenser. The specific construction of the embodiment shown in Figs. 8 and 9, at least for the most part, is the invention of Richard E. Holmes.

The evaporative condenser unit, indicated generally by the reference numeral 40, includes a pan 41, a housing 42 extending down into the pan, a condenser coil 43 and a centrifugal fan 44. A transverse partition 45 separates the spaces which are on the suction and discharge sides, respectively, of the fan 44. A liquid receiver 46 may be disposed within the housing 42, as shown. Water is supplied to the pan 41 by a conduit 47, the flow of the water being controlled by a float valve 48 to maintain a predetermined level, such as that indicated at 49. A plurality of strips 51 are attached to the bottom of the fan housing 42 at the outlet, as shown in Fig. 9, and extend upwardly in an inclined direction across the stream of air which is discharged horizontally from the fan housing. In this embodiment also, the velocity of the air moving horizontally past the strips 51 creates a suction on the back or downstream side of each strip, so that the water lying in the pan 41 is drawn upwardly along the back of the strip and is then carried along by the air onto the air cooled surfaces of the condenser coil 43. I find that with this arrangement the air cooled surfaces of the condenser coil 43 are substantially completely wetted, thereby providing evaporative cooling of the coil, as is well known in the art of evaporative condensers. The air which has passed over the coil 43 and has absorbed sensible heat from the coil, as well as the water vapor resulting from evaporative cooling, is discharged through the outlet opening 52, which may discharge the same either directly outdoors or to any suitable duct connected to the flange 53 surrounding the outlet opening 52.

From the above description it will be seen that

I have provided apparatus for spraying water into an air stream, which apparatus is simple and requires no moving parts other than that used to move the stream of air, and which apparatus I have found to be fully effective to accomplish the desired object.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In a liquid-atomizing device, the combination of means for retaining liquid, said retaining means having an imperforate bottom, means effecting flow of a stream of air at a substantial velocity above the liquid in said retaining means, a strip extending upwardly from the liquid in said retaining means and transversely of said air stream in such manner as to create a suction or reduced pressure on the downstream side of said strip whereby liquid is drawn upwardly from said retaining means and entrained in said air stream, said stream of air flowing on opposite sides of said strip.

2. The combination of receptacle means for retaining a body of water, said retaining means having an imperforate bottom, a strip extending upwardly in an inclined direction from the body of water in said receptacle means, and means for moving a stream of air past the opposite edges of said strip.

3. In apparatus for spraying water, the combination of means providing movement of a stream of air at a substantial velocity, a strip extending upwardly into said stream, and means for delivering water to the downstream side of said strip at the lower end thereof, said water being drawn upwardly along said downstream side of the strip by a suction or reduced pressure created by the velocity of the air stream moving past the opposite edges of said strip.

4. In apparatus for spraying a liquid, the combination of a pan adapted to retain a body of water, the bottom of said pan being imperforate, means for effecting flow of a stream of air at a substantial velocity and in a generally horizontal direction over the water in said pan, and an inclined strip extending upwardly and in downstream direction from the body of water in the pan and into said air stream, said stream of air flowing on opposite sides of said strip.

5. The combination of a pan adapted to retain a body of water, a centrifugal fan effecting a jet of air in a generally horizontal direction over the top of the body of water in said pan, and an inclined strip extending from said body of water into said air stream in an upward and downstream direction, said strip being on the discharge side of said pan, whereby water is drawn upwardly on the under side of said strip and at least partly carried off by said air stream.

6. In apparatus for spraying liquid into an air stream, a centrifugal fan including a casing mounted with its axis of rotation disposed horizontally, said casing being formed with an opening in the bottom thereof and provided with a narrow strip extending upwardly from the upstream side of said opening, the side edges of said strip being spaced from the opposite sides of said fan casing so that liquid entering through

said opening is drawn upwardly on the downstream side of said strip and into said air stream.

7. In apparatus for spraying liquid into an air stream, a centrifugal fan including a casing mounted with its axis of rotation disposed horizontally, said casing being formed with an opening in the bottom thereof and provided with a narrow strip extending upwardly from the upstream side of said opening and spaced from the opposite sides of said casing, and means for delivering liquid to said opening from the outside of the casing to be drawn upwardly along the downstream side of said strip and into the air stream flowing in the casing.

15 8. In apparatus for spraying water into an air stream, the combination of a pan for holding liquid, a centrifugal fan mounted with its axis of rotation disposed horizontally and including a casing having a rounded wall, the lowermost part of said rounded wall being disposed directly above and close to the bottom of said pan and formed with an opening for admission of liquid from said pan into said casing, a narrow strip within said casing extending upwardly from the upstream side of said opening into the air stream motivated by the fan, said air stream flowing past the opposite sides of said strip and creating a suction or reduced pressure on the downstream side of said strip to draw liquid upwardly from said pan through said opening into the fan casing on the downstream side of said strip from whence it is carried into the air stream in the form of a spray.

9. Apparatus for spraying liquid into an air stream comprising means including a fan for effecting flow of a stream of air in a generally horizontal direction, a strip extending upwardly into said air stream, and means for supplying liquid to the downstream side of said strip below the top thereof, the parts being constructed and arranged so that liquid is drawn upwardly along the downstream side of said strip by the reduced pressure produced by the velocity of the air flowing past the opposite sides of said strip.

45 10. Apparatus for spraying liquid into an air stream comprising means including a pan for retaining a body of liquid, a fan discharging a stream of air over said liquid, and a strip extending upwardly from said liquid into said air stream, the parts being constructed and arranged so that liquid is drawn upwardly from said retaining means on the downstream side of said strip by the reduced pressure produced by the velocity of the air flowing past said strip.

55 ARTHUR H. EBERHART.
